UNITED STATES PATENT OFFICE.

ANDREW B. NICHOLSON, OF DENVER, COLORADO, ASSIGNOR TO THE WESTERN OPERA GLASS SUPPLY AND MANUFACTURING COMPANY.

COIN-CONTROLLED LOCKING AND REGISTERING MECHANISM.

SPECIFICATION forming part of Letters Patent No. 408,811, dated August 13, 1889.

Application filed March 25, 1889. Serial No. 304,689. (No model.)

To all whom it may concern:

Be it known that I, ANDREW B. NICHOLSON, a citizen of the United States of America, residing at Denver, in the county of Arapahoe and State of Colorado, have invented certain new and useful Improvements in Coin-Controlled Locking and Recording Mechanism, of which the following is a specification, reference being had therein to the accompanying drawings.

My invention relates to a coin-controlled locking and recording mechanism for application to, use with, and control of the withdrawing-opening of a receptacle for containing articles of merchandise for sale or for hire on the payment of a certain definite sum deposited in the locking mechanism, as a coin or token of the proper denomination, size, and weight. Its objects are to furnish a mechanism of such description of simple construction, very reliable and effective in operation, easily and readily manipulated on the introduction of the proper coin or token, in which the door once opened may not again be closed without the application of a separate device, as a key, that proper attention and care may be insured on the part of the proper attendant; in which the lock-controlling mechanism may be thrown out of operative position by the introduction of a separate device, as a key, in the hands of an inspector or other authorized person, that the interior may be properly inspected at the proper times; in which is combined with the lock-controlling mechanism a recording mechanism recording on a tape, fillet, or band each opening of the receptacle, that record may be had of the exact number of pieces which should be found in the attached closed coin-chamber; to which ends it consists in the features, constructions, arrangements, and combinations more particularly hereinafter described and claimed.

In the drawings is illustrated a typical embodiment of the invention, wherein Figure 1 is a front view of a box with the locking mechanism in locked position on a base-plate therein, the front plate being removed; Fig. 2, a similar view with the mechanism in unlocked position and the lid or cover of the box thrown upwardly; and Fig. 3, a front view, partly perspective, of a receptacle for containing merchandise to which the mechanism is applied.

In the figures, the reference-numeral 1 indicates a base-plate, on which the parts are secured, and which is arranged as a vertical 55 diaphragm in the box, of which 5 is the cover or lid, the front side or plate of the box and mechanism being removed to show the parts. It will be evident, however, that the parts may be secured upon either the front side or plate 60 or the rear one, as herein shown.

Located upon the base-plate and in proper position to engage the hasp, hook, or catch 4, projecting from the cover 5, is the locking-bolt 2, sliding or reciprocating in guideways 65 3, secured to and projecting from the base-plate. A spring 6, herein shown as a helical spring, but which may be any suitable form of spring, is arranged to act on and lift the cover 5 whenever the locking-bolt 2 is released 70 from engagement with the catch 4.

In the body of the locking-bolt is formed a slot or recess 7, in which takes the upper end or head 8 of a lever 9, pivoted or fulcrumed at 10, the movement of such lever then evidently throwing the locking-bolt in one direction or the other. Against the lower or tail end of this lever is arranged a spring 11, arranged to normally hold the lever, so that the bolt is held out of locking engagement 80 with the hook or catch 4, and the cover is allowed to fly and remain open, to which end any form of spring may be used in lieu of the leaf-spring 11 shown. Pivoted at 12 is the dogging-lever 13, arranged so that its inner 85 end may take against the lower or tail end of the bolt-actuating lever 9 and hold the same against the stress of the spring, a stop lug or pin 14 being so situated as to limit the downward movement of the dogging end of 90 the lever 13. Such end, preferably, is rounded or curved, and the upper part of the tail end of lever 9 or the union of tail end and body is curved that the two parts may the more readily move over each other. For brevity 95 this dogging-lever 13 may be termed simply the "dog," and it is evident that this dog, the lever 9, and bolt 2 constitute of themselves a simple and effective locking or bolting mechanism, for the lever 9 when freed from the 100 dog is normally held in one position by the spring, while the dog is adapted to turn it to the other position against the stress of the spring, the movement of the lever either shoot-

ing or retracting the locking-bolt 2, as the case may be, it being evident also that the movement of the dog may be controlled by a handle attached thereto. To now render it 5 coin-controlled, other devices are added as follows: Pivoted above the dog is a lever 15 and so positioned that its ends may take on the dog as the lever 15 is turned and on the end of the dog corresponding to the downwardly-moved end of lever 15. From this 10 lever a handle 16, (herein shown in dotted lines,) should project through the front plate, by which it may readily be swung in one direction or the other, the outer part 15 of such handle being shown in Fig. 3 as a lever or the end of a lever, though the form thereof is immaterial. Above this lever is pivoted at 19 the coin actuated or tilted lever 18, of the general shape of a T-lever; the pivot 20 being at or near the intersection of the upright and transverse limbs. At the outer end of the transverse limb is placed the coin-receptacle 20, of a width and size to just receive the proper coin or token, and to which 25 leads the hopper 28, (indicated in dotted lines,) by which the coin or token is conveyed or guided thereto from the slot 29 in the cover 5, which is also proportioned to the exact size of the piece to be used. Such slot, of 30 course, might be directly over the receptacle 20 and the coin guided directly thereto; but for a more symmetrical appearance of the top it may be placed toward the front and at the longitudinal center thereof and the guiding-hopper 28 used, such position of the slot 35 guarding also against danger of unauthorized operation of the tilting coin-receiving lever by wires or knife-blades. At the opposite end of the transverse limb of lever 18 is a 40 counterbalance-weight 21, just sufficient to overbalance the upright limb and the coin-receptacle arm when there is no coin in the latter. The lower end of the upright arm is bent to the side for a short distance, as shown, 45 by the part 22, in which is formed a slight notch or depression 23, in which takes the pin 17 on lever 15 to normally hold such lever and associated parts in the position seen in Fig. 1, while from the end of part 22 projects a 50 guide-pin or wire tail-piece 24, for contacting with the pin 17 when the parts are in the position seen in Fig. 2. Pivoted at 26 is a pawl 25, having an end adapted to take in the notch 27 in the outer end of the lever 15, falling 55 thereinto by gravity.

As thus far described the devices coacting together form a perfectly-controlled lock mechanism, whereof the operation is as follows: The merchandise being placed in the 60 receptacle and the cover or opening closed and locked, the parts are then in the position shown in Fig. 1, the bolt 2 being shot and engaging the catch of the lid, the dog 13 holding the lever 9 against the force of the spring 11, and being in turn prevented from moving by the inner end of lever 15 taking thereupon on one side and the stop-pin 14 on

the other, the lever 15 being locked in position by its pin 17 catching on the part 22 of lever 18, which is held in position by its counter or overbalance weight 21, all as seen in full lines in Fig. 1.

A coin or token of the proper description is dropped through the slot and reaches the coin receptacle or holder 20, overbalancing 75 the effect of 21 and tipping the lever 18 until the movement of the same be stopped by the pin 46, projecting from the coin-receptacle, taking against dog 13, as shown in dotted lines in Fig. 1. This movement is not sufficient to 80 permit the coin to escape from the receptacle or holder 20, but it remains therein, resting on the bottom thereof and against the side of the case; but it has been sufficient to remove the catch end 22 from contact with the stop-pin 17 on lever 15, which may now be turned in the direction of the arrow, Fig. 1. This being 85 now turned to depress its elevated end, such end takes upon the outer end of the dog 13, causing the dog to be released from holding 90 the lever 9, whereupon the parts are immediately thrown into the position shown in Fig. 2, the locking-bolt being shot, the lid or cover flying open, and the coin-receptacle moving sufficiently to permit the piece therein 95 to escape therefrom, whence it passes through an aperture into the separate closed coin receptacle or chamber 33, pivoted or hinged in any suitable manner to the body of the box, or which may be secured thereto by sliding 100 in grooved ways thereon, and which is secured against opening by a padlock 34 or any other approved form of lock. This form 105 of closed coin-chamber is not shown in the figure, for such forms no part of the gist of the invention, and for that such chamber could be formed in the main box. At the same time the pivoted pawl 25 falls by gravity and its end takes in the notch 17, preventing any retrograde movement of the parts or locking down of the lid, for the accomplishment of which an extraneous appliance must be used by some one intrusted with the devices therefor and with the duty of seeing 110 that the contents of the receptacle are properly replaced or duplicated. To this end a key 30 is inserted and turned so as to lift the pawl 25 from engagement with the lever 15, whereupon such lever is turned in a direction reverse to that of the first movement 115 described, depressing the locking end of the dog, which moves the lever 9 against the force of spring 11, the coin-actuated lever 18 moving by gravity and the parts being restored to the position shown in Fig. 1. If at 120 any time it be deemed desirable to inspect the contents of a receptacle without actuating the mechanism by a coin or token, the inspector uses a similar key, which is turned to take upon the pin 32, projecting from lever 18, and thus cause the tilting of the lever by mechanical force instead of by gravity.

That the number of openings of the receptacle, the number of unlocking movements of

the locking-bolt 2, and hence the amount of money which should be reported may be definitely known at any time, a recording apparatus may be combined with the coin-controlled locking mechanism, and such recording mechanism may be arranged as shown. Upon the pivot 10 of the lever 9 is arranged to rotate a reel or drum 35, upon which may be wound a tape, fillet, or band 10 of paper 43, and with which is formed or to which is secured a ratchet 36. Secured to a lug or post affixed to the base-plate is a spring-pawl 37, taking in the teeth of the ratchet and preventing any retrograde movement of the proper drum, while pivoted on the body of the lever 9 is the spring-acted pawl 38, which locks the drum to the lever for movement in the other direction. The fillet or band 43 may be contained on a feeding-drum secured in the case, or may simply hang loose therein, as shown, behind a stationary or fixed plate 39, passing over the top thereof, where may be a roller 40, and thence down and under a guide pin or roller 41 to the drum or reel 35. Attached to the locking-bolt and projecting therefrom so as to take at its point on rearward motion of the bolt within an aperture 45 in the fixed plate 39 is a stylus 44, adapted to mark or puncture 30 the band or tape. On the back of the fixed plate 39 may be a spring 42, holding the paper band straight and acting as a tension device therefor. Now, as the lever 9 is moved to the position shown in Fig. 2, the pawl 38 carries the drum or reel therewith, causing it to wind up a proportional amount or length of the fillet or band 43. Just as the movement ceases the stylus 44 has reached the fixed plate 39 and imprinted thereon or therein a permanent indication of the movement of the locking-bolt and the opening of the receptacle. The box or receptacle may be furnished with a sufficient number of lugs or ears 47, by which it may be secured to any proper 45 base, or such securing may be by any suitable means. It may be made of any desired size, and the mechanism be operated by any sized or weighted coin or token and for the dispensation of any articles of merchandise 50 or for the withdrawal of any articles intended to be merely hired for a time. In the latter connection it may be used for the hire of opera-glasses, it being exceedingly suitable and desirable therefor.

Having thus described my invention, what I claim is—

1. A coin-actuated locking mechanism consisting of a bolt, a spring-acted lever tending to move it in one direction, a dog locking 60 the lever against such movement, a lever for moving such dog, and a coin-actuated tilting lever locking the dog-actuating lever against movement, substantially as set forth.

2. A coin-controlled locking mechanism consisting of a bolt, a lever for moving the bolt,

a spring tending normally to move the bolt and its lever in one direction, a dog preventing such movement, a handled lever, as the lever 15, for releasing the dog, a coin-actuated tilting lever locking such lever against movement in one direction, and a pawl dropping in position to lock it in the other direction upon release of the locking mechanism and adapted to be removed from engagement therewith by an inserted key, substantially as set 75 forth.

3. A coin-actuated locking mechanism comprising a locking-bolt, a spring-actuated lever tending normally to move the bolt in one direction, means for locking the lever against 80 such movement, a coin-actuated tripping-lever for releasing the locking mechanism, and a pawl holding the locking mechanism in its released condition and adapted to be moved by an inserted key, substantially as set forth. 85

4. The combination of a coin-controlled locking mechanism, a stylus or marker reciprocated thereby, a ribbon of paper marked by the stylus or marker, and means, substantially as described, for moving the paper for a new 90 impression at each operation of the locking mechanism, substantially as set forth.

5. A locking mechanism consisting of a locking-bolt 2, a lever 9, moving the bolt in either direction, a spring acting on the lever to throw 95 it in one direction, and a pivoted dog locking the lever against movement in such direction and adapted to move it in the other direction, substantially as set forth.

6. The combination of the locking-bolt 2, 100 the lever 9, for actuating it, spring 11, dog 13, handled lever 15, lever 18, carrying a coin-receptacle and a counterbalance-weight, and a pawl 25, substantially as set forth.

7. The combination, with a coin-controlled 105 locking mechanism, of a stylus 44, attached to a moving part thereof, a reel or drum for receiving a band or fillet of paper or other markable material, a ratchet 36, and the pawls 37 and 38, substantially as set forth. 110

8. The combination of a locking-bolt 2, carrying a stylus 44, a lever 9, actuating the same, a paper reel or drum having a ratchet 36 and pawl 38 mounted on said lever, a pawl 37, a fixed platen or paper-bed 39, dog 13, handled 115 lever 15, coin-controlled lever 18, and pawl 25, substantially as set forth.

9. The combination of the locking-bolt 2, lever 9, for actuating it, spring 11, acting thereon, dog 13, for acting thereon against 120 the spring, and handled lever 15, for operating on the dog, substantially as set forth.

In testimony whereof I affix my signature in presence of two witnesses.

ANDREW B. NICHOLSON.
